MULTI-COLOR PEN

Emil Hechtle, 118 Elizabeth St., Oradell, N.J.

Filed June 30, 1964, Ser. No. 80,649

Term of patent 14 years

(Cl. D74—17)

FIG. 1 is a top view of a multi-color pen, showing my new design;

FIG. 2 is a front view of the same shown slightly reduced in size compared to FIG. 1.

FIG. 3 is a side view thereof, taken in the direction indicated by the arrow 3, as it appears with one of the writing points in projected position.

I claim:

The ornamental design for a multi-color pen, as shown and described.
